UNITED STATES PATENT OFFICE

135,108

DESIGN FOR A TOOL TRAY OR SIMILAR ARTICLE

Woodrow W. White, Burbank, Calif.

Application February 7, 1941, Serial No. 98,811

Term of patent 3½ years

To all whom it may concern:

Be it known that I, Woodrow W. White, a citizen of the United States, residing in Burbank, in the county of Los Angeles, State of California, have invented a new, original, and ornamental Design for a Tool Tray or Similar Article, of which the following is a specification, reference being had to the accompanying drawing, forming a part thereof.

I claim:

The ornamental design for a tool tray or similar article, as shown.

WOODROW W. WHITE.
